UNITED STATES PATENT OFFICE.

LAURA IDA COLLETT, OF NEVADA, MISSOURI.

UNDERGARMENT.

1,156,757.

Specification of Letters Patent. Patented Oct. 12, 1915.

Application filed September 23, 1914. Serial No. 863,058.

To all whom it may concern:

Be it known that I, LAURA IDA COLLETT, a citizen of the United States, and a resident of Nevada, in the county of Vernon and State of Missouri, have invented a new and Improved Undergarment, of which the following is a full, clear, and exact description.

The invention relates to wearing apparel and its object is to provide a new and improved woman's knit undershirt or vest arranged to snugly fit the body and to be firmly held in place without the use of undesirable and unsightly shoulder straps or sleeves.

In order to accomplish the desired result, use is made of a knit tubular body provided at its upper end with a draw string to permit of drawing the said upper end tight at the wearer's body along a line extending under the arm-pits and over the bust to hold the garment in place without the use of shoulder straps or sleeves.

A practical embodiment of the invention is represented in the accompanying drawings forming a part of this specification, in which similar characters of reference indicate corresponding parts in all the views.

Figure 1 is a perspective view of the undergarment as applied; Fig. 2 is an enlarged perspective view of the undergarment; Fig. 3 is a perspective view of a portion of the draw string; Fig. 4 is an enlarged sectional plan view of the same; and Fig. 5 is a reduced perspective view of a modified form of the undergarment.

The under garment consists essentially of a knit tubular body A provided at its upper end with a beading or a hem B for the reception of a draw string C to draw the upper end of the tubular body A tight around the wearer's body along a line extending under the armpits and over the bust as plainly indicated in Fig. 1. By this arrangement the undergarment is securely held in position on the wearer's body without the use of shoulder straps or sleeves. The lower end of the tubular body A is provided with a ribbing so as to slightly contract the garment at the lower end which latter extends preferably to the lower end of the abdominal region a short distance below the same. It is understood that the garment owing to its elasticity fits snugly on the wearer's body.

The draw string C may be of elastic or non-elastic material but is preferably made

as shown in Figs. 3 and 4 and consists of a back portion C' of elastic webbing and side and end portions C², preferably of non-elastic material. The ends of the back portion C are detachably connected with the rear terminals of the side and front ends by the use of suitable fastening devices E such as heads and sockets, as indicated in Fig. 4. It is understood that it is desirable to remove the elastic back portion C' whenever it is desired to laundry the garment. The front terminals of the draw string are tied into a bow, as indicated in Fig. 2, after the draw string has been drawn sufficiently tight to snugly fit the upper end of the body A of the wearer's body, as previously explained.

If desired the body A may be opened along the front from the upper end to the lower end, as indicated at F in Fig. 5, and the overlying portions fastened together by suitable fastening devices G, such as buttons and buttonholes, otherwise the garment is the same as above described with reference to Figs. 1 and 2.

Having thus described my invention, I claim as new and desire to secure by Letters Patent:

1. As an article of manufacture, a woman's undergarment having a knit tubular body adapted to fit the wearer from under the armpits downward to a distance below the abdominal region, the upper end of the said knit tubular body being provided with an annular beading overlying the wearer's bust and extending under the armpits, and a draw string held in the said beading to permit of drawing the entire upper end of the undergarment tight around the wearer's body to hold the undergarment in place, the said draw string having an elastic middle portion and non-elastic side and end portions.

2. As an article of manufacture, a woman's undergarment having a knit tubular body adapted to fit the wearer from under the armpits downward to a distance below the abdominal region, the upper end of the said knit tubular body being provided with an annular beading overlying the wearer's bust and extending under the armpits, and a draw string held in the said beading to permit of drawing the entire upper end of the undergarment tight around the wearer's body to hold the undergarment in place, the said draw string having an elastic middle portion and non-elastic side and end por-

tions, the said middle and end portions being detachably connected with each other.

3. As an article of manufacture, a woman's undergarment comprising a knit tubular body extending at its lower end to the lower end of the abdominal region and slightly contracted at said end, the said body fitting at its upper end under the arm pits, and a draw-string at the upper end of the tubular body for contracting the same, to hold the garment in place, the draw-string having an elastic back portion and non-elastic side and front portions.

4. As an article of manufacture a woman's undergarment comprising a knit tubular body, adapted to fit at its upper end under

the armpits of the wearer, and a draw-string at the upper end of the tubular body for contracting the same, the draw string having a back portion of elastic webbing and side and front portions of non-elastic material, and fastening devices for detachably connecting the ends of the back portion with the rear terminals of the side and front portions.

In testimony whereof I have signed my name to this specification in the presence of two subscribing witnesses.

LAURA IDA COLLETT.
